BABY DISH

James E. Donaldson, Chicago, Ill.

Application April 5, 1952, Serial No. 19,207

Term of patent 7 years

(Cl. D44—15)

To all whom it may concern:

Be it known that I, James E. Donaldson, a citizen of the United States and resident of Chicago, in the county of Cook and State of Illinois, have invented a new, original, and ornamental Design for a Baby Dish, of which the following is a specification, reference being had to the accompanying drawing, forming a part thereof.

In the drawing, Figure 1 is a plan view of a baby dish, showing my new design;

Figure 2 is a side perspective view of the dish shown in Fig. 1.

I claim:

The ornamental design for a baby dish, as shown.

JAMES E. DONALDSON.
